The essential features of my design reside in the portions shown in solid lines, a conventional attaching stud being shown in broken lines.

I claim:

The ornamental design for a badge or similar emblematic article, as shown and described.
